(57) **CLAIM**

The ornamental design for portable hanging pouch, as shown and described.

DESCRIPTION

FIG. 1 is a front elevational view thereof;

FIG. 2 is a rear elevational view thereof;

FIG. 3 is a left elevational view thereof;

FIG. 4 is a right elevational view thereof;

FIG. 5 is a top elevational view thereof; and,

FIG. 6 is a bottom elevational view thereof.

The even broken lines in the drawings illustrate stitching. The uneven broken lines in the drawings illustrate portions of the portable hanging pouch which form no part of the claimed design.
